UNITED STATES PATENT OFFICE.

JAMES G. McCONNELL, OF CHICAGO, ILLINOIS.

WALL BRACKET FOR MAPS.

Application filed August 7, 1924. Serial No. 730,698.

It is more or less customary to support the maps, charts and the like used in schools either on stands or by supporting the same directly on the wall by means of nails or 5 screws. Such methods of support have various objectionable features as the stands are somewhat awkward to handle and are apt to tip over as well as requiring floor space and if the maps or charts are hung 10 directly on the wall it is difficult to fold them back or raise them to show the succeeding maps where a number are bound together. The present invention relates to means for supporting maps, charts or the like, and 15 more particularly to wall brackets which are adapted to hold the maps or charts in a convenient manner.

The objects of this invention are to provide an improved bracket for holding maps, 20 charts, sheets or the like; to provide a bracket of this character which may be attached to the lower frame member of a blackboard and which will support the maps in an elevated position; to provide a bracket which 25 is adapted to be adjusted to hold the maps at different elevations; to provide a bracket for supporting a plurality of maps so that the maps may be folded over to display the succeeding maps; and, in general, to provide 30 such an improved device as will be described more fully hereinafter.

In the accompanying drawings illustrating this invention:

Figure 1 is a front view showing the device as mounted on a blackboard;

Figure 2 is a somewhat enlarged side view of the bracket;

Figure 3 is a detail of the wall piece and joints;

Figure 4 is a front view of the detail shown in Figure 3; and

Figure 5 is a front view similar to Figure 4 but showing a slight modification.

As shown in Figure 1 the blackboard 6 45 has the usual lower frame member 7 to which my improved bracket is usually attached. This bracket comprises a plate or wall piece 8 which is preferably formed of steel and which is secured to the frame member by means of screws 9. The plate 8 has two oppositely disposed projections 10 adjacent to the lower end thereof for supporting the lower bracket arm 11. A pintle 12 passes through the projections 10 and the inner end of the arm 11 to form a hinge or joint. The inner ends of the projections

10 are bent inwardly or toward each other so that the space between them is slightly less than the diameter of the arm 11 so that when this arm is swung at right angles to the 60 plate 8 it will be pinched between the ends 13 of said projections and when the arm is swung around against the wall or parallel to the plate 8 it will be held in such position by the ends 13. 65

The arm 11 is preferably made of pipe or tubing and is bent upwardly at its outer end where it is threaded to receive an extension tube 14. This extension has a clamp 15 at the top which is provided with a set screw 70 16 for engagement with a telescoping rod 17 for holding such rod in adjusted position. A rod 18 is hooked into or engages with the upwardly turned end of the arm 11 as shown at 19 and is provided with a hook 20 at the 75 opposite end for engagement with the lug or projection 21 on the plate 8. This rod extends downwardly from its point of attachment to the plate, so that it not only serves most effectively as a brace but the 80 outer end thereof is also sufficiently low so that it does not interfere with the maps when they are folded back toward the wall.

The rod 17 engages with a socket 22 on the map head 23 which head is adapted to 85 support one or more maps, charts or the like 24 in the usual manner. The length of the arm 11 is preferably somewhat greater than one half the width of the maps so that the maps may be readily rotated on the rod 90 17 and will clear the wall or blackboard when the bracket is adjusted at right angles thereto. Of course this is not absolutely necessary. When the maps or charts are not being displayed the bracket may be 95 swung back against the wall and the maps will then be held securely in an out of the way position. When the maps are to be displayed, the arm or bracket 11 may be swung out at right angles to the wall where 100 it will be held by the binding action of the projections 10 which will hold it securely in adjusted position. The maps may then be folded over the head backwards toward the wall as the successive maps are to be 105 displayed or the maps may be rotated on the rod 17 to show the opposite sides thereof. With my improved device practically no floor space is occupied except when the maps are being displayed and the maps can not 110 be readily removed or displaced from the bracket.

In the modified form of wall support shown in Figure 5 the projections 10 are shown as having slight grooves or recesses 25 at their outer ends for engagement with the tubular arm or bracket 11 which may in some instances serve to hold the arm more securely than if the frictional engagement alone were depended upon.

While I have shown my improved wall bracket as being especially adapted for use in connection with blackboards it may of course be modified for different uses and therefore I do not wish to limit myself to the exact construction herein shown and described, except as specified in the following claims in which I claim:

1. In a device of the character set forth, the combination of a wall plate, an arm hinged to the lower portion of the plate, 20 means for holding the arm in adjusted position, a brace from the plate to the arm, an upwardly extending pipe at the outer end of the arm and a telescoping rod adjustably secured in said pipe.
- 25 2. In a device of the character set forth, the combination of a wall plate formed of

sheet steel or the like and having two integrally formed projections, the outer portions of said projections being bent toward each other, an arm adapted to engage with 30 said projections, a pintle through said projections and arm, the outer end of said arm being bent upwardly and having a threaded opening, a pipe engaging with said opening, a rod engaging with said pipe, a clamp 35 for said rod and a brace from the plate to the outer portion of the arm, the arrangement being such that the arm will be held in adjusted position by the resilient projections from the plate.

3. A wall bracket for maps, comprising a plate having outwardly extending projections with grooves therein, a tubular arm hinged between said projections and adapted to engage with said grooves when adjusted at right angles to the plate, said plate also having an upper projection, a brace from the upper projectoin to the outer portion of the arm and upwardly extending map supporting means at the outer end of 50 the arm, substantially as described.

JAMES G. McCONNELL.
